LACE TOP STOCKING

Max Junghans, Boonton, N. J., assignor to Van Raalte Company, Inc., New York, N. Y., a corporation of New York

Application June 13, 1951, Serial No. 15,526

Term of patent 14 years

(Cl. D47—7)

To all whom it may concern:

Be it known that I, Max Junghans, a citizen of the United States, residing at Boonton, in the county of Morris and State of New Jersey, have invented a new, original, and ornamental Design for a Lace Top Stocking, of which the following is a specification, reference being had to the accompanying drawing, forming part thereof.

In the drawing:

Fig. 1 is a side view of a lace top stocking showing my new design;

Fig. 2 is an enlarged detail of Fig. 1, partly broken away, showing the design at the top of the stocking and also showing the design which is positioned somewhat below the top of the stocking, it being understood that these designs, respectively, extend around the entire periphery of the stocking.

I claim:

The ornamental design for a lace top stocking, substantially as shown and described.

MAX JUNGHANS.
